UNITED STATES PATENT OFFICE.

WILLIAM R. HUSTON, OF GADSDEN, ALABAMA.

ILLUMINATED SIGN.

1,051,234.

Specification of Letters Patent. Patented Jan. 21, 1913.

Application filed May 6, 1911. Serial No. 625,503.

To all whom it may concern:

Be it known that I, WILLIAM R. HUSTON, a citizen of the United States, residing at Gadsden, in the county of Etowah and State 5 of Alabama, have invented new and useful Improvements in Illuminated Signs, of which the following is a specification.

This invention relates to illuminated signs of that type set forth in United States Patent No. 905,565, granted to C. A. McNeal, Dec. 1, 1908, wherein the letters of the sign are formed by a plurality of light-reflecting disks arranged in the outlines of the letters, the source of light being one or more lamps 15 so disposed that the rays of light strike the disks and are reflected thereby.

The invention has for one of its objects to improve signs of this character so as to obtain a better illuminating effect, impart a 20 better appearance to the sign, at the same time enabling the letters to be made of sheet metal of comparatively light gage.

Another object of the invention is the provision of a sign in which the disks are made 25 of concavo-convex form so that the convex light-reflecting sides give more nearly the appearance of bulbs or beads of light which, taken together with the convexity of the edges of the openings from which the disks 30 are stamped in the plate of the letter, improves the illuminating effect. Furthermore, the convexing of the plate of the letter and of the disks greatly strengthens the 35 letter and enables a sheet of thin gage to be used.

With these and other objects in view, the invention comprises the various novel features of construction and arrangement of parts which will be more fully described 40 hereinafter and set forth with particularity in the claims appended hereto.

In the accompanying drawing, which 45 illustrates one embodiment of the invention, Figure 1 is a front view of a sign letter. Fig. 2 is a vertical transverse section thereof. Fig. 3 is an enlarged detail section through one of the light reflecting disks of the letter.

Similar reference characters are employed 50 to designate corresponding parts throughout the views.

Referring to the drawing, A designates the box or casing of the sign in which may be arranged one or more electric lamps 1 which illuminate the disks 2 of the letters. 55 These disks are stamped from the sheet metal plate 3 that forms the face plate of the

sign and the disks are left attached to the plate 3 by connecting portions 4 at the top of the disks when the latter are wholly bent inwardly, as shown in Fig. 2. It will be observed that the disk is shaped by suitable dies so that its front side will be convex while its rear side 6 is concave, and the edge 7 of the opening formed by punching out each disk, is made convex, with the result 60 that none of the edges of the openings or disks can be seen and the convex surfaces insure a superior illuminating effect. The curving of the disks and front plate of the sign also materially strengthens the letter 70 and permits of the use of comparatively thin metal.

The rays of light from the lamp in the body of the sign strike the convex sides of the disks and are reflected in a generally 75 forward direction, the reflected rays being more in the form of pencils than beams of light due to the curvature of the reflecting surfaces. Some of the rays of light strike the convex edges of the front plate and are 80 in turn reflected from such edges so that the outline of each letter stands out clearly to the vision of the observer.

While the openings and disks in the face plate 3 are disposed to form the various 85 characters constituting the sign, it will be desirable to paint the outlines of the same characters on the front side of the plate 3 with white or other suitable paint or equivalent material, so that the sign can be read 90 by day, the background of the sign being of any suitable color.

From the foregoing description, taken in connection with the accompanying drawing, the advantages of the construction and of 95 the method of operation will be readily apparent to those skilled in the art to which the invention appertains, and while I have described the principle of operation of the invention, together with the device which I 100 now consider to be the best embodiment thereof, I desire to have it understood that the device shown is merely illustrative, and that such changes may be made when desired as are within the scope of the claims 105 appended hereto.

Having thus described the invention, what I claim as new, is:—

An illuminated sign comprising a plate bearing the outline of a character and having 110 a plurality of openings provided within the outline of the character, and a disk formed

on the edge of each opening and extending rearwardly at an angle to the plate, the edges of the opening being curved inwardly to form convex surfaces, and the disks being dished to provide outer convex surfaces for reflecting light coming from the rear of the plate onto the said surfaces.

In testimony whereof I affix my signature in presence of two witnesses.

WILLIAM R. HUSTON.
